HYDROCARBON CONVERSION PROCESS

Louis S. Kassel, Oak Park, and Vladimir Haensel, Hinsdale, Ill., assignors to Universal Oil Products Company, Des Plaines, Ill., a corporation of Delaware

Application December 31, 1954, Serial No. 478,974

5 Claims. (Cl. 260—673.5)

This invention relates to the catalytic conversion of hydrocarbons boiling within the gasoline range. It is more specifically concerned with a novel combination of solvent extraction and catalytic reforming.

The recent developments in the automotive industry, especially in regard to the development of high compression ratio automotive engines, have increased the demand for high octane number gasolines and the petroleum industry has provided technological improvements to produce these high octane number gasolines. One process that has recently received commercial attention is the catalytic reforming process. The term "reforming" is well known in the petroleum industry and refers to the treatment of gasoline fractions to improve the anti-knock characteristics thereof. A highly successful and economical reforming process that has achieved wide commercial acceptance is described in U. S. Patent No. 2,479,110, issued to Vladimir Haensel. However, the present reforming processes are all limited by decreasing yields at increasing octane numbers. There are also other limitations. For example, when a full boiling range straight-run gasoline or a relatively wide boiling range naphtha is reformed in the presence of a catalyst that promotes dehydrogenation of naphthenes and hydrocracking of paraffins, relatively poor yields and considerable fouling of the catalyst are obtained when the operating conditions are selected to obtain large octane number appreciation. This apparently is due to the fact that the relatively severe operating conditions that must be maintained in order to satisfactorily upgrade the higher boiling paraffinic constituents of the feed are too severe for some of the other constituents. The result is that an appreciable part of the feed stock is undesirably converted to gases and to catalyst carbon. Therefore, under the usual conditions of operation the yield of liquid product and catalyst life are limited to a considerable extent by and primarily dependent on the decomposition and carbon forming tendencies of the higher boiling paraffinic constituents and the aromatic constituents. The higher boiling paraffinic constituents may decompose to form coke on the catalyst and the aromatic constituents also deposit coke or carbonaceous material on the catalyst by reacting with each other and forming polynuclear aromatics which are the carbonaceous materials that foul the catalyst. We have invented a method of reforming which largely overcomes these objectionable features of the prior art reforming processes.

It is an object of the present invention to treat a full boiling range straight-run gasoline or a fraction thereof in such a manner that increased yields of high octane number gasoline and aromatics and longer catalyst life are obtained.

In one embodiment the present invention relates to a process which comprises introducing a hydrocarbon charge stock to a separation zone withdrawing from said separation zone a fraction containing a substantial portion of aromatic hydrocarbon and a second fraction containing a substantial proportion of paraffinic hydrocarbons, sub-

2

jecting at least a portion of said second fraction to contact with a dehydrocyclization catalyst at dehydrocyclization conditions thereby forming additional aromatic hydrocarbons, and introducing at least a portion of the reaction product to said separation zone.

In another embodiment the present invention relates to a process which comprises introducing a hydrocarbon charge stock containing paraffins and aromatics to a separation zone, withdrawing from said zone a fraction containing a substantial proportion of aromatic hydrocarbons and a second fraction containing a large proportion of paraffinic hydrocarbons, subjecting said second fraction and hydrogen to dehydrocyclization at dehydrocyclization conditions in the presence of a dehydrocyclization catalyst thereby forming aromatic hydrocarbons, fractionating the resultant stream to remove normally gaseous components therefrom and introducing at least a portion of the resultant stream to said separation zone.

In a further embodiment the present invention relates to a process which comprises introducing a hydrocarbon charge stock containing paraffins and aromatics to an extraction zone wherein said charge stock is treated with a selective solvent having a relatively higher solvent power for aromatics, separately removing from said extraction zone an extract containing said solvent and a substantial amount of the aromatics in said charge and a raffinate containing a substantial amount of paraffinic hydrocarbons, treating said extract to separate the solvent from the aromatics, reforming at least a portion of said raffinate with a dehydrocyclization catalyst at dehydrocyclization conditions in the presence of hydrogen thereby forming aromatics, introducing the reformate from the reforming zone to a first fractionation zone to remove normally gaseous components therefrom, introducing the remaining liquid reformate to a second fractionation zone, fractionating said liquid reformate into a low boiling paraffinic stock containing components lighter than normal hexane and a high boiling fraction, introducing at least a portion of said low boiling paraffinic stock to said extraction zone, and introducing said high boiling fraction to said extraction zone.

Briefly stated, our process comprises solvent extracting a hydrocarbon charge stock to produce a raffinate containing a major proportion of paraffins and an extract containing chiefly aromatic hydrocarbons. At least a portion of the raffinate from the extraction zone is subjected to dehydrocyclization to convert a substantial portion of the paraffins in the raffinate to aromatics. However, in catalytic reforming there occurs some hydrocracking and, therefore, the reformate is fractionated to reject the gaseous hydrocarbons produced in the reforming and the resultant liquid is fractionated to remove a fraction boiling lower than normal hexane since these lighter components are usually high in octane number. All or a portion of the higher boiling fraction is then passed to the same extraction zone that the charge stock is introduced to. The fraction boiling lower than normal hexane is also passed to the extraction zone to provide reflux to the extraction column.

A feature of our process is that the conditions in the reforming zone may be severe enough to convert a substantial portion of the paraffins to aromatics while at the same time minimizing undesirable side reactions which otherwise reduce yields of useful gasoline products. As hereinbefore mentioned, one of the chief reasons for deposit of carbon or carbonaceous material on the catalyst is the reaction of aromatics to form polynuclear aromatics. In our process, however, the aromatics are removed and, therefore, substantially less carbon is formed on the catalyst with resultant longer catalyst life. High severity operation, in the presence of aromatics, is also not desirable from considerations of the chemical equi-

libria involved, as in such operations the aromatics in the feed limit the extent to which such aromatics can be formed from naphthenes and paraffins. In contrast, however, the use of our process involves the removal of a substantial portion of the aromatics from the charge to the reaction zone which thus permits the formation of additional aromatics unrestricted by the limitations of chemical equilibria. Similarly, the isomerization of low octane rating straight chain paraffins to higher octane quality branched chain structure paraffins is an equilibrium chemical reaction. As the isomerization of normal hexane is important to achieve in upgrading gasolines, due to the very limited extent that it undergoes dehydrocyclization at reasonable operating conditions, a feature of our process is that the isohexanes may be continuously removed and the normal hexane recycled to the reaction zone in the raffinate thus obtaining substantial conversion of low octane normal hexane to much higher quality isohexanes with almost no restrictions in yield due to chemical equilibrium considerations.

Therefore, it is preferred to separate the aromatic hydrocarbons from the paraffins and naphthenes in the charge for several reasons. One reason is that reforming the aromatics results in lower over-all yields of reformate presumably due to conversion of some of the aromatics to gaseous hydrocarbons and to hydrocarbons boiling above the gasoline range. Another reason is that high concentrations of aromatics in the reaction zone tend to result in a greater carbon deposition and consequently a shorter process period. Still another reason is that high concentrations of aromatics in the reaction zone tend to suppress the dehydrogenation of naphthenes to aromatics and to suppress the dehydrocyclization of paraffins to aromatics, said dehydrogenation and said dehydrocyclization being equilibrium reactions. By eliminating low octane number high boiling paraffins from the final product the end product is of high quality.

The charge stocks that may be reformed in accordance with our process comprise hydrocarbon fractions that boil within the gasoline range and that contain aromatics and paraffins. The preferred stocks are those consisting predominantly of aromatics, naphthenes and paraffins, although minor amounts of olefins may be present. This preferred class includes straight-run gasoline, natural gasoline and the like. The gasoline fraction may be a full boiling range gasoline having an initial boiling point within the range of from about 50° F. to about 100° F., and an end boiling point within the range of from about 350° F. to about 425° F., or it may be a selected fraction thereof which usually is a higher boiling fraction commonly referred to as naphtha and having an initial boiling point within the range of from about 150° F. to about 250° F., and an end boiling point within the range of from about 350° F. to about 425° F. Mixtures of the various gasolines and/or gasoline fractions may also be used and thermally cracked and/or catalytically cracked gasolines may also be used as charging stock, however, when these unsaturated gasoline fractions are used, it is preferred that they be used in admixture with a straight-run or natural gasoline fraction or hydrogenated before use in our process.

The catalyst that may be used in our invention comprises those reforming catalysts that promote dehydrogenation of naphthenic hydrocarbons and hydrocracking of paraffinic hydrocarbons. Starting with a paraffinic hydrocarbon from a yield-octane standpoint it is preferable to upgrade the paraffinic hydrocarbon by dehydrocyclizing the same to an aromatic than by cracking the paraffinic hydrocarbon. Since the raffinate charge to the reforming zone consists of predominantly paraffinic constituents it is best to upgrade this recycle stream by dehydrocyclization. Therefore it is preferred that the catalyst in the reforming zone be such that it has a substantial amount of dehydrocyclization activity. It is also preferred that the catalyst has paraffin isomerization ac-

tivity to isomerize normal hexane to isohexanes. A satisfactory catalyst comprises a platinum-alumina-silica catalyst of the type described in U. S. Patent No. 2,478,916, issued August 16, 1949. A preferred catalyst comprises a platinum-alumina-combined halogen catalyst of the type described in U. S. Patent No. 2,479,109, issued August 16, 1949. Other catalysts such as molybdenum-alumina, chromia-alumina, and platinum on a cracking catalyst base may be used, however they are not as preferred as the first two mentioned catalysts. As hereinbefore mentioned, it is preferred that the catalyst has substantial dehydrocyclizing activity. We have found that catalysts of the platinum-alumina-combined halogen type, especially those that contain about 0.01% to about 1% by weight of platinum and from about 0.1% to about 1% combined fluorine or those that contain about 0.1% to about 3.0% combined chlorine are especially effective and economical to use in our process because of the long life they exhibit and also they promote dehydrogenation reactions and dehydrocyclization reactions as well as the naphthene dehydrogenation, paraffin hydrocracking and paraffin isomerization reactions.

The operating conditions maintained in the reforming step of our process should be such that substantial conversion of naphthenes to aromatics and relatively mild hydrocracking of paraffins are induced. Further, the operating conditions should be such that there is substantial conversion of paraffinic compounds to aromatics by dehydrocyclization. When employing platinum-alumina-combined halogen catalysts the reforming process will be effected at a temperature within the range of from about 600° F. to about 1000° F., pressure within the range of from about 50 to about 1000 pounds per square inch, and a weight hourly space velocity of from about 0.5 to about 20. The weight hourly space velocity is defined as the weight of oil per hour per weight of catalyst in the reaction zone. It is preferred that the reforming reaction be conducted in the presence of hydrogen. In one embodiment of the process sufficient hydrogen will be produced in the reforming reaction to furnish the hydrogen required in the process; and therefore, it may be unnecessary to introduce hydrogen from an extraneous source or to recycle hydrogen within the process. However, it will be preferred to introduce hydrogen from an extraneous source, generally in the beginning of the operation, and to recycle hydrogen within the process in order to be assured of a sufficient hydrogen atmosphere in the reaction zone. The hydrogen present in the reaction zone will be within the range of from about 0.5 to about 20 mols of hydrogen per mol of hydrocarbon. In some cases the gas to be recycled will contain hydrogen sulfide introduced with the charge or liberated by the catalyst, and it is within the scope of the present invention to treat the hydrogen containing gas to remove hydrogen sulfide or other impurities before recycling the hydrogen to the reforming zone.

The effluent from the reforming zone is usually passed to a stabilizer which effects separation of the normally gaseous material which comprises hydrogen, hydrogen sulfide, ammonia, and hydrocarbons containing from one to four carbon atoms per molecule, from the normally liquid hydrocarbons. A more concentrated aromatic fraction is then obtained in accordance with the present invention by fractionating the stabilizer bottoms to produce fractions of greater and lesser volatility and passing both fractions to a solvent extraction process.

Solvent extraction processes are used to separate certain components in a mixture from other components thereof by a separation process based upon a difference in solubility of the components in a particular solvent. It is frequently desirable to separate various substances by solvent extraction when the substances to be separated have similar boiling points, are unstable at temperatures at which fractionation is effected, form constant boiling mixtures, etc. It is particularly desirable to separate aro-

matic hydrocarbons from a petroleum fraction containing these aromatic hydrocarbons by solvent extraction because a petroleum fraction is normally a continuous mixture of hydrocarbons whose boiling points are extremely close together and because the petroleum fraction contains numerous cyclic compounds which tend to form constant boiling or azeotropic mixtures. As hereinbefore stated, the basis of a solvent extraction separation is the difference in solubility in a given solvent of one of the substances to be separated from the other. It may be, therefore, seen that the more extreme this difference, the easier the separation will be and an easier separation reflects it, process-wise, in less extensive equipment and greater yields per pass in the use of processing equipment as well as in higher purity of product.

A particularly preferred solvent for separating aromatic hydrocarbons from non-aromatic hydrocarbons is a mixture of water and a hydrophilic organic solvent. Such a solvent may have its solubility regulated by adding more or less water. Thus, by adding more water to the solvent, the solubility of all components in the hydrocarbon mixture are reduced, but the solubility difference between the components is increased. This effect is reflected process-wise in fewer contacting stages required to obtain a given purity of product; however, a greater through-put of solvent must be used in order to obtain the same amount of material dissolved.

As hereinbefore stated, the solvent to be used in this invention is preferably a mixture of a hydrophilic organic solvent and water, wherein the amount of water contained in the mixture is selected to regulate the solubility in the solvent of the materials to be separated. Suitable hydrophilic organic solvents include alcohol, glycols, aldehydes, etc. Particularly preferred solvents are diethylene glycol, triethylene glycol, dipropylene glycol, tripropylene glycol, and mixtures thereof containing from about 2% to about 30% by weight of water.

In classifying hydrocarbon and hydrocarbon type compounds according to increasing solubility in such a solvent, it is found that the solubility of the various classes increases in the following manner: the least soluble are the paraffins followed in increasing order of solubility by naphthenes, olefins, diolefins, acetylenes, sulfur, nitrogen, and oxygen-containing compounds and aromatic hydrocarbons. It may thus be seen that a charge stock which is rich in unsaturated compounds will present a greater problem in solvent extraction than a saturated charge stock since the unsaturated compounds fall between the paraffins and aromatics in solubility. Further difficulty in having unsaturated compounds in the feed is that they tend to polymerize at higher temperatures to form sludges and other undesirable materials which causes great difficulty in processing equipment. It may be seen that an ideal charge to solvent extraction is one containing paraffinic and aromatic hydrocarbons exclusively. The paraffinic compounds also differ in their relative solubility in the solvent. The solubility appears to be a function of the boiling point of the paraffin, with the lower boiling or lighter paraffins being more soluble than the higher boiling or heavier paraffins. Therefore, when heavy paraffins are dissolved in the solvent, they may be displaced from the solvent by adding lighter paraffins thereto which displace the heavier paraffins. In an embodiment of this invention it is preferred to recycle the heavier paraffins to the reforming zone and, therefore, a light paraffin is charged to the extraction zone to displace these heavier paraffins from the solvent by putting the heavier paraffins into the raffinate phase.

The light paraffin that is charged to the extraction zone to displace the heavier paraffins may be provided for by removing the light paraffins that are removed from the extraction zone along with the extract. The reformate from the dehydrocyclization zone also may provide a source of light paraffins. In a preferred operation the reformate from the dehydrocyclization zone is fraction-

ated or stabilized to remove normally gaseous paraffins therefrom and the liquid may be passed to a second fractionation zone wherein an isohexane and lighter fraction is removed as overhead and the isohexane and lighter fraction is the light paraffin fraction that is introduced to the extraction zone to displace heavier paraffins from the solvent.

Additional features and advantages of our invention will be apparent from the following description of the attached drawing which illustrates a particular method for conducting a gasoline upgrading operation in accordance with the present invention.

Referring to the drawing a straight-run gasoline fraction having an initial boiling point of 150° F. and an end point of 425° F. is passed through line 1 into a lower portion of extractor 2. In extractor 2 the hydrocarbon material rises and is countercurrently contacted with a descending stream of selective solvent entering the upper portion of extractor 2 through line 4. Water may also be introduced into extractor 2 through line 32 which is shown as entering the top of extractor 2, however, the water may also be added directly to line 4. As hereinbefore mentioned the water is added to increase the selectivity of the lean solvent in line 4.

As a result of the countercurrent contact of the selective solvent and hydrocarbon charge stock, the aromatic hydrocarbons contained in the charge stock are selectively dissolved in the solvent forming an extract stream containing the solvent and aromatic hydrocarbons, and a raffinate stream containing the paraffinic hydrocarbons. The raffinate stream passes from the upper portion of extractor 2 through line 9 while the extract stream passes through the lower portion of extractor 2 through line 8. Line 8 passes to flash drum 19. Flash drum 19 is maintained at a pressure lower than the extractor pressure and preferably is kept at about atmospheric pressure. In the flash drum some of the light paraffinic components are flashed overhead and are removed through line 10. The remainder of the liquid is withdrawn from flash drum 19 through line 11 and introduced to an upper portion of stripper 12 wherein the dissolved aromatic hydrocarbons and dissolved paraffins are separated from the selective solvent. Line 11 is preferably introduced to stripper 12 at a point in the upper half of the column. The separation in stripper 12 is not difficult in that the aromatic hydrocarbons and light paraffins are substantially different in nature from the selective solvent as well as having a substantially different boiling point. The aromatic hydrocarbon stream along with some light paraffins passes overhead through line 13 and combines with the overhead from the flash drum 19 in line 10 and the combined stream in line 14 may be passed to extract rectifier 15. Heat is provided for the stripping operation by reboiler 17 and connecting line 16 and 18. The solvent stream is taken from the bottom of stripper 12 through line 4 and passes through before-mentioned line 4 into the upper portion of extractor 2.

The combined stream in line 14 may be used as the final product, however, it may be subjected to further treatment in order to produce a product of higher quality. In the present illustration the combined stream in line 14 is introduced to an intermediate portion of extract rectifier 15. In extract rectifier 15, the lighter components, chiefly the dissolved light paraffins, are removed overhead through line 20 while the aromatics are removed through line 30. The gaseous material in line 20 passes through cooler 21 wherein the gaseous fraction is liquefied and from cooler 21 the fraction passes through line 22 into receiver 23. A portion of the liquefied overhead stream is passed through line 24 and line 25 into the upper portion of extract rectifier 15 as reflux, and a portion of the liquefied product is withdrawn from receiver 23 through lines 24 and 7 which portion is introduced to the extractor 2 at a point in the lower portion thereof and at a point below the points where lines 1

and 3 enter extractor 2. Heat is provided to extract rectifier 15 by reboiler 28 and connecting lines 27 and 29.

The raffinate stream from extractor 2 which is withdrawn through line 9 may be reformed without further treatment, however, it is preferred that the raffinate stream be further treated in order to improve its suitability for reforming. The raffinate contains dissolved solvent and further the raffinate contains components which may be heavier than are suitable for reforming.

In the drawing the raffinate in line 9 is introduced into glycol separator 35. Separator 35 may be a type of holding or settling tank wherein the glycol entrained in the raffinate is allowed to settle out of the raffinate phase. Separated solvent is removed from separator 35 through line 36 and the remaining raffinate stream is withdrawn from separator 35 through line 37 and subjected to a water-wash in vessel 38. Water-wash column 38 is illustrated as a vertically elongated vessel in which the raffinate is introduced at a lower portion thereof and is counter-currently contacted with a descending stream of water introduced to column 38 in the upper portion thereof through line 39. Water and solvent are removed from vessel 38 through line 40 and the washed raffinate is removed from the upper portion of the vessel through line 41 and introduced to fractionator or rerun column 45.

Rerun column 45 is provided to remove heavy components from the charge to the reforming reactor, however, when the charge does not contain heavy components that are deleterious to the catalyst the rerun column may be eliminated entirely. In the drawing rerun column 45 is provided and heat provided thereto by reboiler 48 and connecting lines 47 and 49. The heavy undesirable components are removed from rerun column 45 through line 50. The overhead from rerun column 45 which comprises the charge stock to the dehydrocyclization zone is removed through line 46 and passes through cooler 51 and line 52 into overhead receiver 53. A portion of the liquid in receiver 53 is withdrawn through line 54 and passes to an upper portion of rerun column 45 through line 55 as reflux. The charge to the dehydrocyclization reaction is removed from receiver 53 through lines 54 and 56, is picked up by charge pump 33 and passed through line 34, combines with hydrogen recycled in line 71, and the combined stream is passed through heater 57 and thence line 58 into reactor 59.

Reforming reactor 59 contains a bed of spherical catalyst of approximately $\frac{1}{8}$ " average diameter containing 0.3 platinum, 0.5% combined fluorine, and 0.1% combined chlorine. The pressure in the reactor is 500 pounds per square inch, the weight hourly space velocity is 4, and the hydrogen to hydrocarbon mol ratio is 6 to 1. During the passage of the charging stock through reactor 59, the bulk of the naphthenes containing six carbon atoms in the ring are dehydrogenated to the corresponding aromatics and a portion of the paraffins are hydrocracked to lower boiling paraffins. Some isomerization of the paraffins also takes place. The important octane number increasing reaction of dehydrocyclization also occurs in reactor 59. By this reaction, a considerable portion of the paraffins are converted into aromatics. This reaction is extremely important in increasing the octane number of the paraffins which are recycled to the reforming reactor. The effluent from reactor 59 passes through line 60, cooler 61, line 62 and into separator 63. Hydrogen is withdrawn from the top of receiver 63 through line 64 and is picked up by compressor 70 and discharged into line 71 and combines with the charge stream in line 34 and passes into furnace 57. Make-up hydrogen may be added to the system through line 65 containing valve 66, or excess hydrogen may be withdrawn from the system through said line.

The liquid hydrocarbons, comprising the reformat and the bulk of the normally gaseous hydrocarbons produced in the process, are withdrawn from receiver 63 through line 75 and passed into fractionator or stabilizer 76. Normally gaseous hydrocarbons are removed overhead through line 77. In stabilizer 76 the normally gaseous material, which includes hydrogen, ammonia, hydrogen sulfide, and hydrocarbon gases containing from 1 to 4 carbon atoms per molecule, is separated from the hydrocarbon liquid comprising substantial aromatic hydrocarbons and paraffinic hydrocarbons. The conditions in the reforming zone or reactor 59 are maintained so that there is substantially no olefinic substances produced. At the conditions hereinbefore specified and in the presence of hydrogen and the catalyst of this invention, olefinic materials will not be produced in any appreciable amounts. The gaseous material passes overhead to line 77 into cooler 78 wherein a portion of the material is condensed and the entire stream passes through line 79 into receiver 80. In receiver 80 the liquid phase and the gaseous phase of the overhead material separate, the gaseous phase passes through line 82 from which it may be vented to the atmosphere or used as fuel or else may be further used in the present process or other processes. The stabilizer has heat provided thereto by reboiler 84 and connecting lines 83 and 85. The conditions in the stabilizer may be such that the gasoline therein is cut deeper, that is C_5 or C_6 hydrocarbons may be removed through overhead line 77, however, in the usual operation only C_4 and lighter components are removed as overhead. It is contemplated that the stabilizer and receiver will operate at a sufficient pressure to liquefy at least a portion of the overhead material so that a liquid reflux stream may be available for return through line 81 to improve the separation in stabilizer 76. The stabilizer bottoms are removed through line 86 and introduced to fractionator 90.

In fractionator 90 the stabilizer bottoms are separated into a light overhead and a heavier bottoms fraction which is fed to the extraction zone 2 through line 3. The conditions in fractionator 90 are maintained so that components which are lighter than those which it is preferred to reform in reactor 59 are removed as an overhead fraction. In the embodiment shown in the drawing the overhead comprises components boiling from the boiling point of isohexane and lighter. The column 90 may be referred to as a deisohexanizer. Components boiling from the boiling point of isohexane and lighter are removed from the deisohexanizer 90 through line 91 and passed into cooler 92 wherein the material is condensed and the entire stream passes through line 93 into receiver 94. The liquid in receiver 94 is withdrawn through line 95. Line 95 splits up into several streams. A portion of the stream in line 95 passes through line 96 into the upper portion of deisohexanizer 90 as reflux. A portion of the liquid in line 95 may be withdrawn through line 97 as product and in some instances may be combined with the product in line 30. A portion of the liquefied stream in line 95, however, is withdrawn through line 6 and passed to a lower portion of extractor 2 as light paraffin reflux. Line 6 enters extractor 2 preferably at a point below which the fresh feed enters through line 1 and preferably below the point wherein line 3, through which the bottoms from fractionator 90, enters extractor 2. This use of the isohexane and lighter fraction in line 6, that is as a reflux to extractor 2, is a preferred feature of the invention. The use of this isohexane and lighter fraction enables much of the heavier paraffins to be displaced into the raffinate and to be recycled to the reforming reactor 59, and thus the combined operation provides a greater utilizing of the product streams and ultimately increases the yield of aromatics and octane number of the final product. Heat is provided to deisohexanizer 90 by reboiler 101 and

connecting lines 100 and 102. Bottoms are removed from the deisohexanizer 90 through line 3 and introduced to a lower portion of extractor 2.

Although the process illustrated in the drawing represents one of the preferred forms of our invention, it is to be understood that our invention is not to be limited thereto. A number of variations may be introduced into the process without departing from the spirit and scope of said invention.

We claim as our invention:

1. A process which comprises introducing a virgin hydrocarbon charge stock containing paraffins and aromatics to a solvent extraction zone wherein said charge stock is treated with a selective solvent containing diethylene glycol and from about 2% to about 30% by weight of water, separately removing from said extraction zone an extract containing said solvent and a substantial amount of aromatics and a raffinate containing a substantial amount of paraffins, treating said extract to separate the solvent from the aromatics, reforming at least a portion of said raffinate with a dehydrocyclization catalyst at dehydrocyclization conditions in the presence of hydrogen thereby forming additional aromatics, introducing the reformate from said reforming zone to a first fractionation zone to remove normally gaseous components therefrom, introducing the remaining liquid reformate to a second fractionation zone and therein fractionating said liquid reformate into a low boiling paraffinic fraction containing isohexanes and lighter components and a high boiling fraction containing aromatics, introducing at least a portion of said low boiling paraffinic fraction to said extraction zone, and introducing said high boiling fraction to said extraction zone.

2. A process which comprises introducing a hydrocarbon charge stock containing paraffins and aromatics to a solvent extraction zone wherein said charge stock is countercurrently contacted with a selective solvent containing diethylene glycol and from about 2% to about 30% by weight of water, separately removing from said extraction zone an extract containing said solvent and a substantial amount of the aromatics in said charge and a raffinate containing a substantial amount of the paraffins in said charge, fractionating said extract to separate the solvent from the aromatics leaving a lean solvent, recycling said lean solvent to said extraction zone, reforming at least a portion of said raffinate with a catalyst comprising alumina, from about 0.01% to about 1% by weight of platinum and from about 0.1% to about 3% by weight of combined halogen at a temperature of from about 600° F. to about 1000° F., a pressure of from about 50 to about 1000 pounds per square inch, a weight hourly space velocity of from about 0.5 to about 20 and in the presence of hydrogen at a hydrogen to hydrocarbon mol ratio of from about 0.5 to about 20 mols of hydrogen

per mol of hydrocarbon thereby forming additional aromatics, introducing the reformate from said reforming zone to a first fractionation zone to remove normally gaseous components therefrom, introducing the remaining liquid reformate to a second fractionation zone and therein fractionating said liquid reformate into a low boiling paraffinic fraction containing isohexanes and lighter components and a high boiling fraction containing aromatics, introducing said high boiling fraction to said extraction zone and introducing at least a portion of said low boiling paraffinic fraction to said extraction zone at a point below the point of introduction of said high boiling fraction.

3. A process which comprises subjecting a virgin gasoline line fraction containing aromatic and paraffinic hydrocarbons to solvent extraction with a polyalkylene glycol solvent in an extraction zone to separate the same into an aromatic extract and a paraffinic raffinate, subjecting the raffinate to dehydrocyclization in the presence of a dehydrocyclization catalyst, fractionating the resultant products and separating therefrom a liquid fraction containing isohexane and lighter hydrocarbons, and introducing at least a portion of said liquid fraction to the lower portion of said extraction zone.

4. A process which comprises subjecting a straight-run gasoline fraction containing aromatic and paraffinic hydrocarbons to solvent extraction with a polyalkylene glycol solvent in an extraction zone to separate the same into an aromatic extract and a paraffinic raffinate, subjecting the raffinate to dehydrocyclization in the presence of a dehydrocyclization catalyst, fractionating the resultant products to separate therefrom a liquid fraction containing isohexane and lighter hydrocarbons and a heavier fraction containing aromatics, introducing at least a portion of said liquid fraction to the lower portion of said extraction zone, and introducing said heavier fraction to the extraction zone at a higher elevation therein.

5. The process of claim 3 further characterized in that said polyalkylene glycol solvent is selected from the group consisting of diethylene glycol, triethylene glycol, dipropylene glycol and tripropylene glycol.
